GAME DEVICE

Meyer M. Marcus, Cleveland Heights, Ohio

Application April 11, 1941, Serial No. 388,116

2 Claims. (Cl. 194—6)

This invention relates to amusement devices and particularly to solitaire or solo games which have automatic timing devices that determine the cycle or duration of time for so playing the game.

The primary object of this invention is to provide a coin operated timing mechanism which meters the duration of or lengths of play time, as well as which aggregates cycles or periods of play time so that they do not run concurrently or overlap if several coins are deposited in the device at one time.

Another object of this invention is to provide a timer of the type mentioned which automatically, accurately and visibly measures the time purchased by the player.

A further object is to provide a time mechanism of this type which is suitable for and adaptable to various types and styles of table games generally known as skill games.

Still another object of the invention is to construct such timing device so that it operates primarily by electrical means and wherein the elements thereof operate quietly and smoothly and which do not require frequent adjustments or repairs.

A still further object is to provide a game of the type mentioned with a clock or time meter which indicates to the player at all times, the amount of time remaining left to play or the cycles or portions thereof paid for but unexpired.

These and other objects and features of the invention will become apparent from a reading of the following description and claims together with the accompanying drawings in which like parts are designated by like reference characters and wherein:

Figure 1 is a comprehensive view of a timer and of a game of a type adaptable for use therewith;

Figure 2 is a diagrammatic view of the mechanism and electrical apparatus used in the timer;

Figure 3 is a side view of an electrically operated brake used to control clock mechanism or meter, the view taken along the line and in the direction of the arrows 3—3 of the Figure 2;

Figure 4 is a sectional view of a gear segment and a gear taken along the line and in the direction of the arrows 4—4 of the Figure 2;

Figure 5 is a sectional view of one of the timing wheels and a contact means engaged therewith used for making and breaking the electric circuit which operates the brake shown in the Figure 3, the view taken along the line and in the direction of the arrows 5—5 of the Figure 2;

Figure 6 is a view of a similar wheel and contact means used for making and breaking the

electric circuit which operates a motor, the view taken along the line and in the direction of the arrows 6—6 of the Figure 2;

Figure 7 is a similar view of another wheel and a twin contact means for making and breaking certain electric circuits taken along the line and in the direction of the arrows 7—7 of the Figure 2;

Figure 8 is an enlarged vertical sectional view of the coin operated switch and coin control mechanism used in the device;

Figure 9 is another vertical sectional view of the same coin operated mechanism taken along the line and in the direction of the arrows 9—9 of the Figure 2;

Figure 10 is a horizontal sectional view of another portion of the same coin control mechanism taken along the line and in the direction of the arrows 10—10 of the Figure 2;

Figure 11 is an elevation of a portion of the meter or clock face used in the device and particularly showing the location of an operation control switch therein;

Figure 12 is a sectional view of a portion of the meter dial and the friction mounted indicating hand thereon taken along the line 12—12 of the Figure 11; and

Figure 13 is a sectional view of a portion of the meter dial showing the meter hand point closing the said operation control switch.

The present invention consists broadly of three main elements. There is first, the game portion 20, the timing mechanism 38, and the coin handling mechanism 70 which is linked with and coordinates the game 20 and the timing mechanism 38. Each of these main parts will be described in detail and in the order mentioned.

The game 20 may be one of many different types or styles of games, but the type of game that this invention is intended for is a solitaire or solo type game played by driving a projectile, generally a ball, on a game board against objects or pins by means of a projector of some sort. The objects or pins usually have different values or ratings and games of this type generally have a method of scoring or tabulating the values or results of the player's efforts, so that the skill of the player can be easily measured, tabulated or compared with results of their previous efforts. The Figure 1 shows a game of this type, and in this figure, the game board is indicated by the character 21, the projectile by 22, the projector or driver by 23, and the pins or objects by 24. A game of this type is generally mounted on rather sturdy and solid legs such as those indi-

cated by the character 25. The game 20 has a lock or release pin 26 which releases either one or more of the projectiles or balls 22 for playing and under the circumstances and conditions hereinafter mentioned.

The timer referred to and broadly indicated by the character 30, consists of an electrically operated clock or meter 31 having a dial 32 which closely resembles the dial of an ordinary clock, that is, it is calibrated and marked off into time periods or cycles. The illustration of Figure 1 shows, for example, a meter or clock dial 32 marked off in six periods of ten minutes each. There is only one hand or pointer 33 on the timer which moves rather rapidly in a clockwise direction to indicate the amount of playing time purchased by the player, but which hand 33 moves back or counter-clockwise more slowly and at a normal rate of speed to indicate the number of minutes left to play.

The electric clock or timer 30 is also provided with an aggregating or allocating device which is termed and referred to herein as a collocating mechanism and which consecutively moves the pointer or indicator 33 clockwise in proportion to or in a number of degrees commensurate with the number of coins inserted in the device at the coin slot 73. The collocating mechanism is composed of a gear 34 which is rigidly mounted on the meter or driven shaft 35. The gear wheel 34 has a number of teeth 45 evenly and regularly spaced around its entire peripheral surface. Engageable with the gear 34 is a gear segment 36 on the wheel 37 which is fixed to the drive shaft 33. The gear segment 36 has teeth 46 thereon which engage the teeth 45. The segment 36 covers only a sixty degree portion of its peripheral surface so that while the two wheels 34 and 37 have the same diameter the wheel 34 will revolve one-sixth of a revolution to the one revolution of the wheel 37. The degree of arc of the segment 36 corresponds to the degree of movement of the pointer 33 caused by the deposit and action of one coin only. The gears 34 and 37 together with their related parts and apparatus is referred to herein as an electrically operated eccentric gear device.

The timer 30 is also provided with a magnetic or solenoid operated brake which serves to more accurately control the pointer 33 so that it does not jump or permit the game to be played except when time has been properly purchased. In the schematic Figure 2 and the Figure 3 of the drawings the meter brake is shown as having a conventional brake drum 39 suitably surfaced and mounted on the drive shaft 35. Surrounding the drum 39, there is a flexible brake band 40 which has one end secured to timer case 41 and the other end secured to the solenoid piston 43. The construction is such that when the solenoid 42 is energized, the brake band 42 is loosened and the drum 39 is allowed to rotate freely. When the solenoid 42 is not energized, the spring 44 draws the piston or core 43 away from the drum 39 and tightens the band 40. This stops the clock and prevents the indicator 33 from moving on the meter dial 32 as aforesaid. The clock mechanism 31 may be a conventional electrically operated clock modified or reversed so that its pointer runs counter-clockwise instead of clockwise and changed simply so that the pointer or hand 33 could make one complete revolution around the dial 32 in sixty minutes instead of in twelve hours.

In combining the timer 30 with the game device 20, the timer may be mounted at the rear

end of the game in an upright position as shown, or it may be mounted on the side and flat if more convenient. At any rate, it should be well illuminated so that the time periods purchased and the minutes remaining left to play are always visible to the player.

The coin handling mechanism 70 has first of all a coin deposit box 71 which is mounted on the game 20 at a place convenient and easy for the player to reach. The box may be provided with a slug ejector so as to discard counterfeit coins. The ejector is not shown in the drawings because it is generally an accessory, and ejectors suitable for the purpose are well known to the art and available on the market. After a coin 72 is deposited in the slot 73, it eventually finds its way into the coin chute 74 and continues to drop through the chute until its passage is restricted by the two metal fingers 75 and 76 or blocked by another coin. The chute 74 is lined with a layer of hard rubber 79 or some other suitable insulation or dielectric material.

As soon as the coin 72 strikes the two fingers 75 and 76, an electric circuit is closed which sets into motion the timer 30 and unlocks the game playing means 26 so that the ball 22 may be projected thereby. The details of the electric circuits performing and controlling these operations will be described in detail hereinafter. The finger 76 is movable and at certain predetermined moments, it is drawn outward and it thereby permits the coin 72 to drop into a lower chamber 78 from where it passes into a suitable box or bank which, however, is not shown in the drawings. Simultaneously with the withdrawal movement of the finger 76, a third finger 77 which is a little above the former two is moved inwardly into the insulated chute 74 and thereby blocks the downward movement or further passage of the next succeeding coin which is indicated in the drawings by the character 72a. As long as a coin 72 contacts both the fingers 75 and 76, an electric circuit, also referred to herein as a primary electric circuit, causes a small electric motor to operate. The aforesaid elements 72, 75 and 76 constitute a simple momentary electric switch.

In the Figure 2, the movable finger 76 is shown holding the coin 72, while the Figure 8 shows the third finger 77 blocking the passage of the coin 72a.

At this point it may be well to describe the construction of the coin handling means, particularly the part shown in the enlarged views of Figures 8 and 9 and which part is referred to herein as the initial handling means. The coin chute 74 is just wide enough and deep enough to permit the smooth passage therethrough of a single coin or several coins edge to edge and in line. The chute 74 has across its width two aligned channels, one of which securely receives the fixed finger 75 and the other channel 79 slidably receives the movable finger 76. These two channels are electrically and suitably insulated by the linings 79a and 79b as is clearly shown in the Figure 8.

The solenoid 103 is mounted on the case to the side of the channel 79 so that the core 103a is in line therewith. The outer end of the core 103a has a collar 103b integral therewith and a coil spring 107 thereon. The spring 107 is of the compression type and tends to urge the core 103a toward the chute 74. The finger 76 is connected or linked to the core 103a by means of the dielectric block 108.

Mounted on the solenoid is an arm 97 on which there is attached, at the pivot pin 98 the lever 99, one end of which, to wit, the lever end 99a, is flexibly fastened to the collar 103b and the opposite end of which, namely, the upper end 99b, is flexibly fastened to the insulated arm 100. This link and lever construction just described is such that when the finger 76 is inside the chute 14 the finger 77 is outside thereof, and vice versa.

The lower part of the coin handling mechanism, the part thereof including the chamber 78, is referred to herein as the final handling means. This portion has a solenoid 104 which is connected in parallel with the solenoid 103 and therefore operates simultaneously therewith. The core 104a is provided with the fixed collar 104b and the compression spring 109 so as to eject the core when the solenoid is de-energized. The second solenoid 104 is mounted on the timer case slightly below the first solenoid 103 and is operated at a right angle thereto.

A lever 142 is pivoted on the shaft 145. One arm, the right arm 143 in the drawing of Figure 10, is hingedly connected to the core 104a by means of the slideable pin 146 in the slot 147. The left arm 144 of the lever 142 has two parallel spring leaves 149 and 150 which are provided therebetween with contact points forming an automatic switch 92 which makes or breaks certain contacts in an electric circuit hereinafter described in detail. As solenoid 104 is engaged the switch 92 is automatically opened because the member 148 is freed and certain tension thereon is released which permits it to spring away from the arm member 150. The end of the arm leaf 149 is provided with a short peg or finger 141 mounted on an insulated block 151. The length of the finger 141 is enough to cause the closing of the switch 92 when a coin 72 is in the chamber and also sufficient to cause the switch 92 to remain open when the chamber 78 is empty. Therefore, if there is no coin in that part of the handling mechanism referred to as the final handling portion, the game lock 26 cannot be released due to the immobility of the solenoid 106.

Slightly below the solenoid 104, there is still another solenoid 105, similarly provided with a core 105a, a collar thereon 105b and a compression spring 105c. As the solenoid 105 is energized, it operates the lever 152 which is pivoted to the time meter frame 41 at the point 153. The top end of the lever arm 154 is flexibly connected to the movable gate 140 which slides in the tracks 155 mounted on the chute 14. At a certain period in the cycle the solenoid 105 is energized through the contact wheel 88 for a rather short time. This causes the gate 140 to open long enough to permit the tensioned finger 141 to eject the coin 72 from the chamber 78. Simultaneously therewith, the switch 92 is automatically opened and thus breaks the circuit for the game lock solenoid 106. This mechanism also controls the timer as well as the game lock 26. The motor and related mechanism indicated by the character 80 and heretofore referred to operates through a suitable speed reduction device or differential which is not shown in the drawings as it forms no part of this invention and further, drives the series of contact wheels 81, 85, and 88 which open and close certain auxiliary electric circuits herein-after described in detail. In the Figure 2 the motor mechanism 80 is shown as driving the

shaft 38 on which the contact wheels 81, 82, and 83 are mounted.

The contact wheel 81 is shown in detail in the Figure 6 and consists of a small hard rubber wheel around which a metal drum 82 is firmly secured. Two friction contacts 83, having lead wires 83a and 83b are mounted adjacent to the drum so that when the drum is in a certain position the primary or initial circuit is closed. The wheel, however, has a small insulated portion which is indicated by the character 84 which is not covered by the metal and which breaks the primary circuit when the contact 83 is located thereon. The Figure 6 shows the relative positions of the wheel 81 and the contact members 83 when the circuit is open.

A wheel 85 similar to wheel 81, is mounted on the shaft 38 and has a smaller contact portion 86 and two friction contact members 87a and 87b. The contact member 86 on the wheel 85 is shorter than the one on the wheel 81 and has a length which corresponds with and is co-ordinated with the gear segment 36 heretofore referred to.

The third contact wheel 88 is similarly constructed and mounted. It has a metal contact portion 89 thereon and has two pairs of contact members 90 and 91. In the drawing of Figures 2 and 7, the top pair of contact members 90a and 90b close the circuit connected with one part of the coin handling mechanism, referred to as the initial handling means, and lower pair of contact members 91a and 91b are connected with another part of the coin handling mechanism referred to as the final coin handling means.

There is another small switch referred to as switch 92 that is mounted on the back of the timer dial 32. One of the switch arms 94 of this switch projects through a small slot 95 in the dial face and is closed by the pressure of the indicator hand 33 thereon when the hand is in the ending or zero position. The action of the switch 93 shorts the pair of contacts 91 so that at the end of each time period paid for or at certain predetermined certain moments of a multiple time cycle or aggregation of periods, the finger stop portion of the coin handling mechanism will be in a condition for receiving or allowing the passage therethrough of a coin.

In order to prevent the clock mechanism 31 from becoming damaged in the event more than six coins are accidentally deposited in the receptacle 71 at one time, which excess deposit will drive the collocating device gear wheel 34 and the indicator hand 33 for more than one revolution, thus causing the hand 33 to strike the back of the projecting spring leaf or arm 34, the indicator hand 33 is not rigidly mounted on the shaft 35. Instead, there is interposed between the hand 33 and the shaft 35 a small spring which absorbs the shock and jar of excess reverse movement.

Broadly, there are two distinct electric circuits in this device. There are the circuits referred to herein as the primary or major circuit which sets the motor mechanism in operation at the beginning of the game, and the several minor circuits which, when taken together are referred to as the secondary or minor circuit and which operate the timing device, the unlocking means, the collocating mechanism, and the coin handling mechanism, heretofore referred to and separately described.

Each of the circuits will be described herein-after and inasmuch as some of the conductors shown in the Figure 2 serve more than one cir-

cuit, the lines representing their conductors will, in some instances, have two or more reference characters.

In the Figure 2, the power line is indicated by the characters 110. The primary circuit has a conductor 111 connected to the power line and to the stationary finger 75. It has a conductor 112 connected to the movable finger 76 and to the relay 101 and a conductor 113 going from the relay 101 to the main power line 110. When the relay 101 is energized, it closes the circuit which consists of a conductor 128 which leads from the main line 110 to the motor 80, conductor 114 from the motor 80 to the relay switch 101a and the conductor 115 from the relay switch 101a to the main line 110.

The circuit which is closed by the operation of the contact wheel 81 consists of a conductor 116 which leads from the main line 110 to the revolving contact drum 81 to the contact member 83a, through the metal rim 82 to the contact member 83b and by way of the conductor 117 to the relay 101 and from there to the main line by way of the conductor 113. The closing of this circuit, by the action of the contact wheel 81, shorts or retains the circuit or connection initially formed by the fingers 75 and 76 and the coin 72, when there is no coin in the lower portion of the chute 74. The time taken for one complete revolution of the wheel 81 constitutes the time of play referred to herein as a cycle or a time period, and which, for the sake of simplicity, will be referred to and indicated herein as a ten minute period.

The circuit closed by the wheel 88 and the pair of contact members 90 is formed by the conductor 118 which connects the power line 110 and the friction contact member 90a; the conductor 114 which connects the contact member 90b with the solenoid 103 and the solenoid 104 which two solenoids operate mechanism in the coin operating device 10. The conductor 120 connects the two solenoids 103 and 104 with the main line 110.

The contact wheel 88 also closes a circuit which consists of the conductors 121, connecting contact member 91b with the power line 110, and conductor 122 which connects the solenoid 105 to the friction contact member 91a, and the conductor 123 which connects the solenoid 105 to the other side of the main line 110. The contacts 91a and 91b are shorted by way of the conductors 124 and 125 which lead to and from the contact switch 93 heretofore referred to, when the wheel 88 is in the position substantially as shown in the Figure 7 and when the indicator hand 33 is in the zero position.

The circuit formed by the wheel 85 and the contact members 87a and 87b consists of the conductor 126 which connects the main line 110 to the friction contact member 87a, the conductor 127 which connects the friction contact member 87b to the solenoid 42, and the conductor 128 which connects the solenoid 42 to the main line 110. The friction contact members 87a and 87b are shorted by means of the conductors 129, 130, and the relay switch 102a when the relay 102 is energized.

The relay 102 is energized by the circuit consisting of conductor 131 which leads from the main line 110 thereto and the conductor 132 which leads from the relay 102 to the switch 92 and through the switch 92 to the main line 110 by way of the conductor 133. The conductor 133 also has therein the solenoid 106, which when

energized draws the finger 106a away from the shoulder 26a of the game locking device so that the lock 26 may be released. The solenoid 106 is shown in the Figure 2 as being connected to the conductor 133 by means of the two wires 133a and 133b. In the circuit just described, the solenoid 106, being connected with the relay 102 and the timer mechanism 31 in series, functions simultaneously therewith.

10 The timer mechanism electric clock heretofore referred to is electrically connected by the conductor 134 which leads from the main line 110, and the conductor 135, the switch 92 and the conductor 133.

15 Before the start of the game, the projectiles 22 are made immovable with the game lock 26. The time indicator 33 is at the zero point, and the timing wheels 81, 85, and 88 are in the positions shown in the Figures 5, 6, and 7 respectively.

20 The wheels 34 and 37 are engaged as shown in the Figure 4. The switches 101a and 102a are open and the solenoids 103, 104, 105, and 106 are dead. As soon as the coin 72 is dropped in the chute 74, the relay switch 101a is closed. This puts the motor 80 in operation. The electric circuit completed by the wheel 81 keeps the switch 101a in its closed position and shorts the coin handler 70. The wheel 80 revolves at a fixed rate of speed and makes one complete revolution for each period or cycle of playing time, which in this case is ten minutes. At the same instant that the motor starts running, the contact wheel 85 energized the solenoid 42 thereby loosening the brake 39 and starts operating mechanism in the clock 31. At the same instant that the brake 39 is loosened, the wheel 37 drives the wheel 34 sixty degrees which in turn causes the meter indicator 32 to advance to the point "10" on the dial. The clock being simultaneously energized, causes the meter hand 33 to move counter-clockwise at a normal rate of speed. Also, at the same instant, this switch 92, being closed, the solenoid 106 is energized and the lock 26 is released so that a

35 predetermined number of projectiles 22 are released by a forward push for the player's use. At the same time, the relay 102 is energized and the switch 102a is closed thereby so that the clock brake 39 is kept off during the entire playing period.

40 Shortly after the aforesaid initial operation takes place the contact wheel 88 by way of the members 89 and 90 energizes the two solenoids 103 and 104 simultaneously. The solenoid 103 releases the coin 72 so that it drops down into the chamber 78, the finger 141 first having been removed by the solenoid 104. The gate 140 then being closed holds the coin in the chamber until released by the action of the solenoid 105.

45 The contact wheel 88, by way of the members 89 and 91 opens the gate 140 at a predetermined time so that the coin 72 therein drops into the coin box below and makes room for the next coin 72a.

50 When the solenoid 104 moves the lever 142 on the pivot 145, the switch 92 is opened so that the core pin 106a tension by the spring 106c will lock the projectile release member 26. When the playing cycle or period comes to an end, the indicator hand 33 causes the contact members 93 and 94 to close so that the solenoid 105 will open the gate to permit the last coin to drop out.

55 If additional coins are placed in the machine so that more than one period of play time is purchased at the beginning of the game, then the

finger 11 in the coin handling mechanism blocks the passage of the additional coins until the solenoid 103 is de-energized by the breaking of the contact at the points 89 and 90 of the wheel 88. This construction permits as many as six coins to be inserted in the machine at one time so that as many as six playing cycles or one hour of playing time may be purchased. For example, if two coins are deposited the indicator hand 33 will move to "20" on the dial; and similarly if three coins are deposited the hand will move to the point "30" before starting to move slowly back to "0." The design of the coin handling mechanism and the collocating mechanism is such that the periods automatically follow each other successively and consecutively without overlapping or without noticeable break and without the performance of any special act by the player.

While the invention has been disclosed somewhat schematically in its preferred form, it is to be understood that the embodiment of the invention as described and illustrated herein is not to be considered in a limiting sense as there are many other forms or modifications of the invention which are also considered to be within the scope of the appended claims.

I claim:

1. In an amusement game device, a coin operated lock and playing period timer therefor, comprising in combination, a major electric circuit having a coin operated switch member therein and including an electric motor controlled by a relay operated by the said member; and minor electric circuits each having an electric switch therefor operated by the said motor, the first of the said minor circuits operating a means for removing a coin from the said coin operated switch member, the second of the said minor circuits short-circuiting the aforesaid member in a manner whereby the said relay will continue to control the said electric motor after a coin is removed from the said member, and the third of the said minor circuits opening the aforesaid lock and simultaneously operating a meter for measuring a playing period of the game.

2. A device of the kind defined in claim 1, and further characterized by the coin operated switch member and the minor electric circuits being connected in a manner whereby the meter in one of the minor circuits indicates the aggregate of the playing periods in correlation with the number of coins passing through the said switch member during a playing period.

MAYER M. MARCUS.
